UNITED STATES PATENT OFFICE.

WILLIAM W. QUINTON, OF NORTHBIDGE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,316,059.

Specification of Letters Patent. Patented Sept. 16, 1919.

Application filed March 9, 1918. Serial No. 221,417.

To all whom it may concern:

Be it known that I, WILLIAM W. QUINTON, a citizen of the United States, residing at Northbridge, in the county of Worcester and State of Massachusetts, have invented an Improvement in Feeler Mechanisms for Looms, of which the following description, in connection with the accompanying drawings, is a specification, like characters on the drawings representing like parts.

The invention to be hereinafter described relates to feeler mechanisms for looms, and more particularly to the detecting end of the feeler members of such mechanisms.

In that type of feeler mechanisms where the feeler member is moved longitudinally of the shuttle at the critical point of exhaustion, the feeler member is usually provided with a toothed or serrated end which, by engagement with a working supply of filling in the shuttle, prevents movement of the feeler member longitudinally of the shuttle, but when the filling has become substantially exhausted, such toothed or serrated portion is permitted to move longitudinally along the filling carrier or bobbin and initiate filling replenishment. In feeler motions of this type, the feeler member must be sensitive to either the presence or substantial absence of filling in the shuttle, and in the latter event, its movement longitudinally of the shuttle must be effected promptly upon detection of substantial exhaustion.

An important feature of the present invention, therefore, consists of a feeler member, the detecting end of which will make known either the presence or substantial exhaustion of the filling in the shuttle, and in the latter event, will facilitate movement of the feeler member in a direction longitudinally of the shuttle. In carrying this feature of the invention into effect, the detecting or rear end of the feeler member is provided with a toothed portion for engagement with the filling, and a relatively movable part or roller which, when the filling is substantially exhausted, will facilitate movement of the feeler member longitudinally of the shuttle.

Another important feature of the invention consists of a feeler member, the detecting end of which is formed of a metallic and non-metallic portion, the former becom-

ing ineffective when the filling reaches a predetermined degree of exhaustion, thereby allowing the non-metallic member to contact with the filling or carrier in the shuttle to control the movement of the feeler member.

The above and various other features of the invention will best be made clear from the following description and accompanying drawings of one good, practical form of the invention.

In the drawings:

Figure 1 is a side elevation of a portion of a feeler member embodying the present invention;

Fig. 2 is a view similar to Fig. 1, with the detecting or rear end of the feeler member shown in section on the line 2—2, Fig. 3;

Fig. 3 is a view looking at the detecting end of the feeler member;

Fig. 4 is a section on the line 4—4 of Fig. 1;

Fig. 5 is an enlarged view showing the general action of the feeler member during the presence of a working supply of filling in the shuttle on a detecting beat; and

Fig. 6 is a cross-sectional view through the filling carrier or bobbin showing the action of the feeler member when the filling is substantially exhausted.

The present invention is more especially directed to the detecting or rear end of the feeler member of the so-called "side swipe" feeler, wherein the feeler member is moved longitudinally of the shuttle on a detecting beat when the filling is substantially exhausted, to thereby initiate filling replenishment, and while adapted for advantageous use in connection with the "side swipe" form of feeler mechanism, is, nevertheless, capable of advantageous use in connection with other types of feeler motions. Inasmuch as the present invention relates solely to the detecting or rear end portion of the feeler member, only so much of the feeler mechanism is shown and described as appears necessary for a proper understanding of the construction and mode of operation of the invention itself.

In the drawings: The feeler 1 may be of any usual type. The detecting or rear end of the feeler member 1 may be variously associated with the feeler member itself, but in the present instance, the detecting or rear end 2 of the feeler member is shown as a

part made separate from and secured to the feeler member. This, of course, may be otherwise contrived.

The detecting end 2 of the feeler member 5 is slotted as at 3, thereby forming the side portions 4 which are provided with a toothed part 5 for engagement with the filling on a detecting beat. The side portions 4, as well as the teeth 5 of the detecting end 10 of the feeler are preferably formed of metal.

Mounted in the slotted portion 3 of the detecting end of the feeler member is a roller 6 which may be appropriately supported between the side members 4 of the detecting end 15 by means of a pivotal support 7, the construction being such that the roller 6 may be free to rotate between the side portions 4, substantially as indicated in Figs. 3 and 4. The roller 6 has its peripheral edge portion extending slightly rearwardly or beyond the toothed portion 5 of the feeler end, substantially as indicated in Figs. 1 and 2, the construction being such that upon a detecting beat the peripheral portion of the roller 6 will sink into the filling and permit the teeth 5 of the metallic side portions 4 to engage and be held by the filling.

Disposed between the side portions 4 of the detecting end of the feeler member is a 30 non-metallic portion or member 8 which may be provided with teeth 9 corresponding to the teeth 5 of the side portions 4. The non-metallic member 8 may be formed of fiberoid, or similar substance.

35 When the feeler member is in feeling position, substantially as indicated in Fig. 5, and the filling carrier 10 is provided with a working supply of filling 11 on a detecting beat, the roller 6 will sink into the filling 40 and permit the metallic toothed portion 5 at each side of the non-metallic toothed portion 8 to engage the mass of filling and hold the feeler member from movement longitudinally of the shuttle. As the diameter of 45 the filling carrier becomes less and less, its cylindrical surface will present less and less area for engagement by the teeth 5 of the metallic portion of the detecting end of the feeler until, when a predetermined degree of 50 exhaustion of filling has been reached, as indicated graphically by Fig. 6, the metallic toothed portion 5 of the detecting end of the feeler will no longer engage the few coils of remaining filling or the filling carrier, but these will be then engaged by the 55 teeth 9 of the intermediate non-metallic portion 8. The teeth 9 of the non-metallic portion 8 will then control the movement of the feeler member, and when the filling has 60 come substantially exhausted, and the roller 6 no longer sinks sufficiently far into the filling to permit its engagement by the teeth 9, the feeler member will move longitudinally 65 of the shuttle to initiate filling replenishment.

When the filling is substantially exhausted as indicated in Fig. 6, the peripheral portion of the roller 6 and the non-metallic teeth 9 will alone engage the filling or the filling carrier and, owing to the character of these 70 parts, will not injure the filling carrier or bobbin.

The above described construction has been found especially advantageous when used with coarse or soft yarn, although it may be 75 employed with advantage in the finer and harder spun yarn.

Claims:

1. A feeler member, the rear end of which is provided with a toothed part to be held 80 from movement longitudinally of the shuttle on a detecting beat by engagement with the filling, and a part movable relative to the toothed part to facilitate movement of the rear end of the feeler member longitudinally of the shuttle.

2. A feeler member having a rear end comprising a toothed portion and a rolling portion, movable relatively to the toothed portion.

3. A feeler member having a rear end provided with a rolling surface.

4. A feeler member having a toothed part to engage the filling and a roller mounted on the feeler member to present its periphery for engagement by the filling on a detecting beat.

5. A feeler member, the detecting end of which comprises a toothed part and a roller.

6. A feeler member having a detecting 100 end provided with a toothed part and a recess, and a roller mounted in the recess.

7. A feeler member having a detecting end provided with a toothed part and a recess, and a roller mounted in the recess with 105 its periphery extending beyond the toothed part.

8. A feeler member having a single detecting end comprising a toothed non-metallic portion and a toothed metallic portion both of which portions on the single detecting end engage a surface within the shuttle.

9. A feeler member having a single detecting end comprising a toothed non-metallic portion and a toothed metallic portion at each side of the toothed non-metallic portion.

10. A feeler member having a detecting end including a toothed metallic portion to engage the filling on a detecting beat until predetermined exhaustion of filling, and a non-metallic portion relatively fixed with respect to the toothed metallic portion for engaging the filling or carrier when the toothed metallic portion ceases to engage the filling on a detecting beat.

11. A feeler member having a detecting end including a toothed metallic portion to engage the filling on a detecting beat until 120

predetermined exhaustion of filling, a non-metallic portion engaging the filling or carrier when the toothed metallic portion ceases to engage the filling on a detecting beat, 5 and a member mounted on the detecting end of the feeler member for movement relative to the toothed portions.

12. A feeler member having a detecting end including a toothed metallic portion 10 to engage the filling on a detecting beat until predetermined exhaustion of filling has been reached, a non-metallic toothed portion engaging the filling or carrier when the toothed metallic portion ceases to engage the 15 filling, and a roller carried by the detecting end of the feeler member.

13. A feeler member having a detecting end provided with a toothed non-metallic portion, and a toothed metallic portion at 20 the side of the toothed non-metallic portion, and a relatively movable portion in line with the toothed non-metallic portion.

14. A feeler member having a rear end comprising a toothed portion and a portion 25 movable relative to the toothed portion as the feeler end moves longitudinally of the filling carrier.

15. A feeler member having a single fill-

ing engaging end to enter the shuttle comprising a metallic engaging portion and a 30 non-metallic engaging portion arranged side by side in different horizontal planes to contact with different horizontal portions of a surface within the shuttle.

16. A feeler having its rear end portion 35 provided with a member mounted for non-sliding movement in contact with and along a surface within the shuttle as the end of the feeler moves longitudinally of the shuttle on a detecting beat.

17. A feeler member having a single detecting end portion to enter the shuttle and feel for the filling, said end portion comprising a metallic member and a non-metallic member to engage a surface within 45 the shuttle on a detecting beat.

18. A feeler member having a rear end to enter the shuttle, comprising a surface movable relatively to the rear end of the feeler member in a direction longitudinally 50 of the filling carrier as the rear end of the feeler member moves longitudinally of the filling carrier.

In testimony whereof I have signed my name to this specification.

WILLIAM W. QUINTON.
